(57) CLAIM

The ornamental design for portions of multi-function equipment housing, as shown and described.

DESCRIPTION

FIG. 1 is a front perspective view of portions of multi-function equipment housing showing our new design; FIG. 2 is a rear perspective view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The dashed lines shown in the figures disclose unclaimed structure, are for environmental purposes only, and thus form no part of the claimed design. The dotted lines shown in the figures represent the border between claimed subject matter and unclaimed subject matter and form no part of the claimed design.
